1 Claim

ABSTRACT OF THE DISCLOSURE

An athletic shoe for minimizing the possibility of injury to the legs or knees of the wearer comprising an upper, a sole, tapered cleats at the toe and heel of the sole, and a safety traction block between the toe and heel cleats and having a plurality of ground-engaging ribs depending therefrom.

With athletic shoes of the prior art, a plurality of tapered cleats are provided on the shoe sole. Usually these shoes have five or more cleats, usually three positioned by the toe and two positioned by the ball of the foot and two or three positioned under the heel.

With such prior art shoes, when a player is in motion, running forward or backward or trotting, the cleats are sunk deeply into the ground up to the sole of the shoe itself. If a player is running hard, the cleats carry the full weight of his body and terrific pressure is applied directly to the ball of the foot. At times, the cleats get caught or "hung up" in the ground with each step. The momentum, or running action of the player's legs, will yank out the cleats with no apparent effort. However, when the player's momentum is suddenly stopped, that is when he may be tackled low, from the side or from the back, the loss of the leg pumping rhythm will cause the feet to be solidly planted at the same time as an opposing force, the tackler, may exert great pressure against the body, with the usual result of a break or fracture of the lower leg, or a torn knee cartilage.

The shoe of the invention was developed to do away with leg injuries to athletes wherefore, when the player is hit, the body, and the legs, go with the momentum of the opposing force, while still giving above average, if not better, traction as compared with the conventional athletic shoe.

The shoe hereof reduces to almost nil the chances of knee or leg injuries to an athlete.

In the drawings:

FIG. 1 is a front elevational view of a shoe embodying my invention;

FIG. 2 is a bottom plan view thereof;

FIG. 3 is a rear elevational view thereof;

FIG. 4 is a perspective view of the sole thereof;

FIG. 5 is a rear elevational view showing the shoe in a first flexed position;

FIG. 6 is an end elevational view of the shoe of FIG. 5, as seen from the left thereof;

FIG. 7 is a rear elevational view showing the shoe in a second flexed position; and

FIG. 8 is an end elevational view of the shoe of FIG. 7, as seen from the right thereof.

A shoe embodying the invention includes an upper 10 of high or low cut design and a sole 12, which sole is provided on its lower face with downwardly-directed cleats 14 at the toe end of the shoe and with downwardly-directed cleats 16 at the heel end of the shoe, cleats 14 and 16 being of usual and well-known tapered hard rubber design wherefore a detailed description thereof will not be here offered.

Also disposed on the lower face of sole 12, interme-

2

diate toe cleats 14 and heel cleats 16, is a safety traction block 18 having a plurality of integral, spaced, parallel, laterally-extending saw-tooth like, ground-engaging ribs 20 depending therefrom.

Ribs 20 are downwardly and rearwardly directed and extend transversely across the full width of the safety traction block and of the sole.

The safety traction block is preferably formed from hard rubber or plastic and is fixed to the sole in any convenient manner. Alternatively, the sole and traction safety block could be integrally formed.

It will be observed that the plane of the apices of ribs 20 is disposed upwardly of the plane of the apices of cleats 14 and 16. This is of importance since the safety traction block is disposed directly below the major weight bearing portions of the foot and especially below the ball of the foot.

Cleats 14 and 16, extending below the plane of ribs 20, permit the toe and heel to dig deeper into the ground than the ribs so that the wearer retains a maximum mobility but at no time is the shoe sole completely trapped in the earth or turf.

When the wearer is running, the ribs engage the earth or turf, but not so deeply or positively as the cleats.

This feature is shown diagrammatically in FIGS. 5 and 7 wherein the earth or turf is represented by the imaginary line T. In FIG. 5, the toe cleats are clearly shown as being more deeply embedded than are the ribs, and in FIG. 7, the heel cleats are clearly shown as being more deeply embedded than are the ribs.

Accordingly, the shoe affords full traction for running, sudden stops and other maneuvers, but is easily releasable from its engagement in the turf or earth because of the shallow penetration of the ribs.

Thus, even should a player be tackled when his foot is firmly implanted in the ground, the shoe will "give" or will not "hang-up," thereby materially minimizing the possibility of leg injuries.

The arrangement of three cleats at the toe and two at the heel is optional, but preferred. It is essential, however, that no cleats be provided at the ball area of the foot since this is the major weight bearing area.

In this area, the traction safety block is used to maintain maneuverability while minimizing the possibility of injury.

I claim:

1. An athletic shoe for minimizing the possibility of injury to the legs or knees of the wearer comprising, an upper, a sole, tapered cleats depending from the toe and heel of the sole, and a safety traction block depending from the sole and extending between the toe and heel cleats, the safety traction block having a plurality of ground-engaging ribs depending therefrom, with the plane of the apices of the cleats being disposed below the plane of the apices of the ribs.
